UNITED STATES PATENT OFFICE.

JOHN T. QUIGLEY, OF BOSTON, MASSACHUSETTS, ASSIGNOR TO COSTMETER COMPANY, OF BOSTON, MASSACHUSETTS, A CORPORATION OF MASSACHUSETTS.

FILING AND INDEXING EQUIPMENT.

1,387,010.

Specification of Letters Patent. Patented Aug. 9, 1921.

Application filed November 2, 1918. Serial No. 260,848.

To all whom it may concern:

Be it known that I, JOHN T. QUIGLEY, a citizen of the United States, and a resident of Boston, in the county of Suffolk and 5 State of Massachusetts, have invented an Improvement in Filing and Indexing Equipment, of which the following description, in connection with the accompanying drawings, is a specification, like characters on 10 the drawings representing like parts.

This invention relates to filing and indexing equipments of the class in which the cards or sheets are arranged with their identification-bearing margins in overlapping 15 relationship, so as to present them all to view at one time, and aims to provide an equipment of this class in which provision is made to permit one or more sheets to be offset from the remainder by shifting them 20 lengthwise of their respective sheet-holders.

My invention will be best understood by reference to the following description, when taken in connection with the accompanying drawings of one specific embodiment there- 25 of selected for illustration, while its scope will be more particularly pointed out in the appended claims.

In the drawings:

Figure 1 is a front elevation of an illustrative filing and indexing equipment embodying my invention, showing the same as 30 it appears with some of the sheets offset;

Fig. 2 is an elevation of one of the sheets and sheet-holders, showing the sheet un- 35 folded;

Fig. 3 is a sectional view on line 3—3 of Fig. 1, showing the sheet uplifted preparatory to the operation of offsetting the same;

Fig. 4 is a sectional view, similar to Fig. 3, 40 but showing the sheet-holder flexed or bowed, and the sheet unlocked from the sheet-holder; and

Fig. 5 is a sectional view similar to Fig. 4, but showing the sheet shifted laterally to 45 bring the offset of the sheet holder into registration with another perforation in the sheet in readiness for reengagement therewith.

Referring to the drawings, and to the embodiment of my invention which is illustrated therein, I have shown for purposes of exemplification a filing and indexing equipment comprising a plurality of sheets 50 arranged with their identification-bearing 55 margins in overlapping relationship,

said sheets being held by sheet-holders 11, whose terminal portions 12 (see Fig. 3) are mounted in suitable bearings in an appropriate mounting 13, the latter being herein of common form having a pair of inwardly-projecting flanges 14 forming channels 15 to receive the terminal portions 12. Preferably the latter are cylindrical, and form trunnions about the axes of which the sheets and sheet-holders may be turned to present 60 either face of the sheet to view. The trunnions rest on one another and maintain the identification bearing margins in properly spaced relationship, there being provided suitable means, herein upper and lower stops 65 16 and 17, to prevent the trunnions from shifting lengthwise of the channels. The sheets may be arranged and re-arranged from time to time, by removing the sheets and sheet-holders, and placing them in the 70 desired arrangement. This may be accomplished by bending, or bowing, the sheet-holder to reduce its length, and to allow its terminal portions to be withdrawn from or 75 replaced in the channels.

To facilitate the removal and replacement of the sheet-holders, the latter are herein made of suitable resilient material, such as tempered wire, which permits them to be bowed, so that their ends may be withdrawn 80 from beneath the retaining flanges 14. The resiliency of the wire is utilized for other important purposes, which will presently appear.

The sheet holders are attached to their 85 respective sheets by folding the latter and providing them with perforations 18 adjacent the fold of each sheet, the sheet-holder extending through one of these perforations into and along said fold, and out through 90 the other, as clearly shown in Fig. 3, thus forming a readily attachable and detachable connection between the sheet and sheet-holder. To remove the sheet from the sheet-holder, the latter is first sprung out of its 95 place in the mounting, and then the sheet-holder is shifted lengthwise while maintaining its bowed form to facilitate withdrawing the trunnions 12 through the perforations 18. The sheets and sheet-holder may 100 be re-assembled by a reversal of the foregoing operation.

Under some circumstances, it is desirable to offset one or more of the sheets, thereby 105 to distinguish them temporarily from the 110

others, or in other words to constitute a signal or signals. This is well illustrated in Fig. 1, in which I have shown several of the sheets offset toward the left, and 5 several offset toward the right, from the others, by shifting them lengthwise of their respective sheet-holders. It is obvious that, in order that this may be done, the mounting 13 should have suitable provision for 10 permitting lateral displacement of the sheets with relation to the mounting, as by having its flanges 14 spaced apart a distance substantially greater than the width of the sheets. It is desirable that when the sheets 15 are thus offset, they shall be locked, in order to prevent accidental derangement. It is also desirable that the sheets which are not offset shall be similarly locked against accidental movement. I have, therefore, made 20 provision for causing the sheets and sheet-holders to interlock with each other in a plurality of positions.

To these ends, I have provided the sheet and sheet-holder with suitable interengaging means, utilizing the resiliency of the 25 sheet-holder to permit disengagement and rearrangement of such means by flexing the sheet-holder. This may be done in various ways, as by providing the latter with an offset 30 19, (see the upper central portion of Fig. 1) which may be received in any one of a plurality of perforations 20, herein three, adjacent the fold of the sheet and suitably spaced according to the needs of 35 the situation. Usually the offset will be received in the middle perforation, and the sheet will be normally positioned thereby in the middle of the mounting. If, now, it is desired to offset the sheet toward the right 40 or left, this may be done by simply grasping the sheet, turning the same at an angle to the plane of the sheet-holder, and then exerting an outward pull which will result in flexing and bowing the sheet-holder, as well 45 illustrated in Fig. 4, thereby withdrawing the offset 19 from the perforation 20, which it normally occupied. While still maintaining the sheet-holder under stress, the sheet is then shifted in one direction or the other, 50 to bring the offset 19 into registration with the desired perforation 20, as well illustrated in Fig. 5, whereupon the sheet is released and the sheet-holder straightens, thus causing the offset to enter the new perforation, whereupon the sheet is locked in its new position. It is obvious that any suitable number of perforations may be employed to provide the desired number of offset positions.

60 This means for offsetting the sheets and locking them in each of their offset positions is one of great utility, as it may be made use of for a wide variety of purposes in various lines of business when running through an index or file, since each sheet which it is de-

sired to reserve for future attention may be distinguished from the others either temporarily or permanently by laterally offsetting the same in one direction or the other to the desired degree. The advantage of this 70 should be readily apparent, especially in the case of accounting operations, where posting, checking and recapitulating are done. This is of special advantage in connection with an index or file of the overlapping type, 75 because all of the offset sheets are presented to view at one time, and without the necessity of handling them.

Having thus described one specific embodiment of my invention, but without 80 limiting myself thereto, what I claim and desire by Letters Patent to secure is:

1. In an equipment of the class described, the combination of a sheet and a sheet-holder extending through said sheet, said sheet and 85 sheet-holder having coöperating interengaging means providing for securing them in any one of a plurality of predetermined relative positions with respect to the length of said sheet-holder. 90

2. In an equipment of the class described, the combination of a folded sheet and a sheet-holder extending through the fold of said sheet, said sheet and sheet-holder having coöperating interengaging means provided for securing them in any one of a plurality of predetermined relative positions with respect to the length of said sheet-holder. 95

3. In an equipment of the class described, 100 the combination of a sheet provided with a plurality of perforations, and a sheet-holder extending through one or more of said perforations and provided with laterally projecting means normally received in an other perforation. 105

4. In an equipment of the class described, the combination of a sheet provided with a plurality of perforations, and a sheet-holder extending through one or more of said 110 perforations and provided with laterally projecting means receivable in any one of a plurality of other perforations.

5. In an equipment of the class described, the combination of a folded sheet provided 115 with a plurality of perforations adjacent the fold, and a sheet-holder received in said fold and extending through one or more of said perforations and provided with laterally projecting means receivable in any 120 one of a plurality of other perforations.

6. In an equipment of the class described, the combination of a sheet, a resilient sheet-holder, and bearings for the terminal portions of said sheet-holder, said sheet and 125 sheet-holder being interengaged at a plurality of points and having coöperating means inter-engageable in any one of a plurality of other definite positions, and utilizing the resiliency of said sheet-holder to per- 130

mit disengagement and reengagement of said means by flexing said sheet-holder.

7. In an equipment of the class described, the combination of a sheet provided with a plurality of perforations, a resilient sheet-holder engaged with a plurality of said perforations and having laterally projecting means receivable in any one of a plurality of others of said perforations, and bearings for the terminal portions of said sheet-holder, said means being adapted to enter into and withdraw from said latter perforations by flexing said sheet-holder.

8. In an equipment of the class described, the combination of a sheet, a resilient sheet-holder, and bearings for the terminal portions of said sheet-holder, said sheet and sheet-holder being interengaged at a plurality of points and having coöperating means inter-engageable in any one of a plurality of other definite positions, said means being disengageable and reengageable by bowing said sheet-holder intermediate said bearings.

25 9. In an equipment of the class described, the combination of a sheet, a resilient sheet-holder, and bearings for the terminal portions of said sheet-holder, said sheet and sheet-holder being interengaged at a plurality of points and having coöperating means inter-engageable in any one of a plurality of other definite positions, said means being disengageable and reengageable by pulling said sheet laterally thereby to bow said sheet-holder intermediate said bearings.

10. In an equipment of the class described, the combination of a folded sheet provided with a plurality of perforations adjacent the fold, and a sheet-holder comprising a resilient wire extending through one of said perforations into and along said fold and out through another of said perforations, said wire being provided with a lateral offset normally received in another of said perforations, said offset being disengageable from and reengageable with any one of a plurality of said perforations by flexing said wire.

45 11. In an equipment of the class described, the combination of a plurality of sheets having overlapping margins, a plurality of sheet-holders comprising wires extending through their respective sheets, the latter being mounted to shift longitudinally, and a

mounting for said sheet-holders, said sheet-holders and mounting being constructed to 55 permit one or more of said sheets to be offset with relation to the remainder by shifting such sheet or sheets longitudinally of their respective sheet-holders, and said sheets and sheet-holders having coöperating means to 60 retain said sheet or sheets so offset.

12. In an equipment of the class described, the combination of a plurality of sheets having overlapping margins, a plurality of sheet-holders comprising wires extending 65 through their respective sheets, and adapted to permit the latter to shift longitudinally, and a mounting for said sheet-holders, said mounting having provision to permit one or more of said sheets to be offset with relation 70 to the remainder by shifting such sheet or sheets longitudinally of their respective sheet-holders, said sheet being provided with one or more perforations and said sheet-holder being provided with laterally projecting means adapted to engage therewith to 75 retain said sheets in the desired positions with reference to said sheet-holders.

13. In a filing equipment, the combination of a series of overlapping sheets, and a series 80 of flexible sheet-holding means interengaged with said sheets at a plurality of points in each, and having other portions interengaging with said sheets, respectively, and disengageable therefrom by flexing said sheet- 85 holding means.

14. In a filing equipment, the combination of a series of overlapping sheets, each provided with a plurality of perforations, and a series 90 of flexible sheet-holders one for each sheet engaged with a plurality of said perforations and having means entering one of the other perforations of its respective sheet, said means being shiftable from one perforation to another by flexing said sheet. 95

15. In a filing equipment, the combination of a series of overlapping sheets, and a series of flexible sheet-holding means, each sheet and sheet-holding means being interengaged at a plurality of points and having means interengageable in a plurality of other definite positions and disengageable by flexing said sheet-holding means. 100

In testimony whereof I have signed my name to this specification.

JOHN T. QUIGLEY.
